HANDLE FOR GLASS CUTTER OR SIMILAR ARTICLE

Thomas A. Insolio, Bristol, Conn., assignor to The
Fletcher-Terry Company, Farmington, Conn.

Filed Apr. 29, 1971, Ser. No. 138,850

Term of patent 14 years

Int. Cl. D8—03

U.S. Cl. D8—51

FIG. 1

FIG. 2

FIG. 3

FIG. 4

FIG. 5

FIG. 6

FIG. 7

FIG. 1 is a perspective view of a handle for a glass cutter or similar article incorporating the present design.

FIG. 2 is a vertical front elevational view of the handle shown in FIG. 1.

FIG. 3 is a top view of the handle shown in FIG. 1.

FIG. 4 is a vertical rear elevational view of the handle shown in FIG. 1.

FIG. 5 is a bottom view of the handle shown in FIG. 1.

FIG. 6 is a front end view of the handle shown in FIG. 1.

FIG. 7 is a rear end view of the handle shown in FIG. 1.

I claim:

The ornamental design for a handle for a glass cutter or similar article, as shown.
